Patented Apr. 10, 1973

226,673

SERVING TRAY

Robert F. Bateman, St. Paul, Minn., assignor to
Plastics, Inc., St. Paul, Minn.

Filed Feb. 8, 1971, Ser. No. 113,786

Term of patent 14 years

Int. Cl. D7—99

U.S. CL. D44—10 E

FIG. 1

FIG. 2

FIG. 3

FIG. 4

FIG. 5

FIG. 6

FIG. 1 is a top plan view of a serving tray, showing my new design;

FIG. 2 is a front perspective view;

FIG. 3 is a front elevational view;

FIG. 4 is an end elevational view;

FIG. 5 is an enlarged fragmentary perspective view of a portion of the tray as viewed along line 5—5 of FIG. 1;

FIG. 6 is an enlarged fragmentary perspective view of a portion of the tray as viewed along line 6—6 of FIG. 1; and

FIG. 7 is a perspective view thereof.

I claim:

The ornamental design for a serving tray, as shown.
